UNITED STATES PATENT OFFICE.

CHARLES A. HARP, OF BUFFALO, TEXAS.

CHICKEN-COOP.

1,214,780.

Specification of Letters Patent.

Patented Feb. 6, 1917.

Application filed November 13, 1916. Serial No. 131,106.

To all whom it may concern:

Be it known that I, CHARLES A. HARP, a citizen of the United States, residing at Buffalo, in the county of Leon and State of 5 Texas, have invented a new and useful Chicken-Coop, of which the following is a specification.

The present invention appertains to chicken coops, and aims to provide a novel 10 and improved chicken coop which will be sanitary and provided with novel means to exclude insects, snakes, rats and other rodents.

Another object of the invention is to provide 15 a chicken coop constructed of plastic or other suitable material and embodying a novel assemblage of the component elements, and having novel means therein for the nests.

It is also the object of the invention to provide a structure of the nature indicated which is simple and inexpensive in construction, the parts of which can be readily separated for cleaning, and which is practical 20 and satisfactory in use.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:—

Figure 1 is a front view of the coop. Fig. 2 is a plan view thereof with the cover or top 40 removed. Fig. 3 is a diametrical section taken on the line 3—3 of Fig. 1.

In carrying out the invention there is provided a base 1 of circular or other suitable contour and formed of suitable plastic material, which is also true of the other parts 45 of the coop, although various materials can be used. The base 1 is provided with an annular rabbet 2 providing a seat for an upright cylindrical body 3 forming the

annular or continuous wall of the coop, and 50 the rabbet 2 provides a shoulder 4 around which the body 3 fits to hold it in concentric position upon the base.

The base is provided with an annular trough or moat 5 surrounding the seat 2 55 and which is filled with water, so that the moat will exclude insects, vermin, rodents, and the like, from the inclosure or chamber of the coop, and furthermore, the moat will hold water for the chickens to drink from. 60 The surface of the base is preferably beveled or sloped off, as at 6, surrounding the moat or trough 5 whereby the overflow water can readily flow to the ground from the moat or trough, and the provision of the 65 beveled or sloped portion 6 also prevents the vermin or rodents from jumping across the moat.

The body 3 is provided with an annular series of ventilating openings 7 adjacent to 70 its upper edge, and the upper edge of said body has an outer bevel 8 for shedding water. A circular top or cover 9 fits within the upper edge of the body 3 and is provided with an annular flange 10 seating upon 75 the upper edge of the body. The cover 9 sheds water to the sides of the coop.

A crescent-shaped or arcuate member 11 is seated upon the base and fits the body 3, said member 11 being sloped outwardly, as 80 at 12, to provide an arcuate space for the nests. The body 3 is provided with a lower opening 13 for the passage of the chickens into and out of coop, and outside of the opening 13 the body has a cut away portion 85 providing a chordal surface 14 against which a door 15 is fitted for horizontal sliding movement upon the base. The body 3 has a chordal groove 16 extending above the opening or doorway 13 slidably receiving the 90 upper edge of the door, and the base 1 has a groove 17 below and parallel with the groove 16 for slidably receiving the lower edge of the door. The door has suitable means 18 whereby it can be conveniently slid 95 open and closed.

The cover or top 9 can be removed, and the base 1, body 3, top or cover 9, member 11 and

door 15 can be readily separated for cleaning or replacement, said members being formed of plastic or other suitable material.

Having thus described the invention,
5 what is claimed as new is:-

1. A chicken coop embodying an annular body, and an arcuate member fitting the same and sloped outwardly to provide a space for nests.
- 10 2. A chicken coop embodying a base, an annular body seated thereon, and a crescent-

shaped member seated upon the base and fitting the body, said member being sloped outwardly to provide a space for nests.

In testimony that I claim the foregoing as 15 my own, I have hereto affixed my signature in the presence of two witnesses.

CHARLES A. HARP.
